UNITED STATES PATENT OFFICE.

HARRY N. ATWOOD AND DAVID D. STERNBERGH, OF READING, PENNSYLVANIA.

EQUALIZING DRIVE MECHANISM FOR AIRSHIPS.

1,148,280.

Specification of Letters Patent. Patented July 27, 1915.

Application filed April 29, 1915. Serial No. 24,652.

To all whom it may concern:

Be it known that we, HARRY N. Atwood and DAVID D. STERNBERGH, citizens of the United States, residing at Reading, in the county of Berks and State of Pennsylvania, have invented certain new and useful Improvements in Equalizing Drive Mechanism for Airships, of which the following is a specification.

Our invention relates to the drive mechanism for aeroplanes or like machines, and consists in the novel arrangement of propelling devices and driving means therefor hereinafter fully described in connection with the accompanying drawing and the novel features of which are pointed out in the claims. In these machines the action of each propeller upon the air exerts a driving forward action upon the machine; this action being exerted in pushing forward the mass of the machine when the propeller is located rearwardly thereof, while if it is located forwardly it exerts a pulling action thereon. If propellers be located both forward and rearward of the machine, their pulling and pushing actions respectively will coöperate in driving the machine forward, with a less strain upon the supporting frame-work than if only forwardly located, or only rearwardly located, propellers are employed. Moreover if the actions of the forwardly located and rearwardly located propellers be equalized, the balance of the machine will be automatically maintained by their normal operation; the tilting tendency incident to the employment of either forwardly or rearwardly located propellers alone, being avoided even though the plane in which the propeller axes are most conveniently located be far above or below the median horizontal plane of the machine, and lateral equilibrium being maintained by the symmetrical arrangement of the propellers relative to the central vertical plane of the machine. In order that this automatic balance may be secured however, it is requisite that the effective actions of the several propellers be constantly equalized under actual conditions of service. The joint operation of both forwardly located and rearwardly located propellers, arranged in parallel planes of rotation, involves great changes of air conditions in each of said planes due to the action thereon of the propellers operating in the other plane, which changes vary with the speed of rotation of the propellers

and with the velocity of the machine itself and of the natural air currents. The equalization of the effective actions of the symmetricaly arranged propellers must therefore be promptly and automatically insured in order that the desired equilibrium of the machine may be maintained, and the mechanism employed must be simple in order to satisfactorily meet ordinary requirements.

Our invention consists essentially in providing in the simple manner hereinafter described, for the accomplishment of these results; and it at the same time permits of definitely varying the relative speeds of the propellers as required to effect or facilitate the steering of the machine when desired.

Figure 1 is a diagrammatic plan view illustrating our invention as applied in simple manner to an air-ship of the hydro-aero-plane type; and Figs. 2 and 3 are similar front and side elevations of the same respectively.

The essential character of the several devices employed in our improved machine as indicated, being well known, and the invention consisting in the novel combination and arrangement thereof only, these devices are merely indicated diagrammatically without showing of their specific construction; and the type of machine to which they are applied is merely illustrative. The motor 2 and seats 3 are mounted upon a supporting frame-work which comprises, as indicated, a floatable body portion 4 to which upper and lower planes 5 and 6, with standards 7, and rear rudder mechanism, are suitably secured.

The motor shaft 10 is shown operatively connected to a differential gearing indicated at 11; said gearing being adapted to equally divide the power, in well known manner, between transversely alined drive-shaft sections 12, 13, through which propeller shafts on opposite sides of the machine are respectively driven. Each of these drive-shaft sections is provided with a braking device, 14 and 15, which may be separately operated by a conveniently located lever 16 so as to unequally divide the power transmitted through the differential gearing 11 to the shaft sections 12, 13 when desired, as has been heretofore proposed in connection with propeller arrangements commonly employed.

In our improved apparatus, each propeller shaft carries a single propeller, but is

connected with another propeller shaft by differential gearing operatively connected to the drive-shaft 12, 13; and the propellers of these connected shafts are located respectively forward and rearward of the machine so as to exert respectively a pulling and pushing effect thereon, which effects are equalized under all conditions by the connecting differential gearing; so that with a symmetrical arrangement of the propellers relative to the central vertical plane of the machine, the combined action of the propellers will automatically maintain the machine in equilibrium. Each of the forwardly located pair of propellers 20, 20, as shown, is fixed to a suitably mounted shaft 21, which is connected by a differential gearing 22 to a drive-shaft section 12 or 13, and also to an alined propeller shaft 23 carrying a rearwardly located propeller 24; so that the power transmitted through said drive-shaft section, 12 or 13, will be equally divided between said front and rear propellers 20 and 24, notwithstanding any inequality of air conditions under which they respectively operate, whether such inequalities be due to the churning action of the adjacently arranged propellers themselves or otherwise. Thus if one propeller were operating in a partial vacuum as compared with another it would be automatically speeded up relatively so as to equalize the working effect and maintain the equilibrium of the machine. Even in case of possible breakage, this automatic action would safeguard the machine and permit of cutting off the motor if desired. The preferred form of drive shaft illustrated, with its differentially driven and brake-controlled sections, permits the operator to guide the machine by relatively speeding up the propellers on one or other side of the machine, while at the same time maintaining equalized action of the front and rear propellers on the respective sides thus enabling a satisfactory control of the machine which is otherwise impracticable.

The selected embodiment of our invention which is specifically shown and described

may obviously be modified without departing from the invention as pointed out in the claims.

What we claim is:

1. In an air-ship, the combination with a supporting frame and motor, of a pair of front-propeller shafts, a pair of rear-propeller shafts each of which is connected to a front-propeller shaft by a differential gearing, and a common drive shaft for all of said propeller shafts. 50

2. In an air-ship, the combination with a supporting frame, a motor-shaft, and a propeller drive-shaft comprising separate sections and a connecting differential gearing, of a pair of front-propeller shafts, and a pair of rear-propeller shafts each of which is connected to a front-propeller shaft by a differential gearing operatively connected to one of said drive-shaft sections. 60

3. In an air-ship, the combination with a supporting frame, a motor-shaft, and a propeller drive-shaft comprising separate sections and a connecting differential gearing, of a pair of front-propeller shafts, and a pair of rear-propeller shafts each of which is connected to a front-propeller shaft by a differential gearing operatively connected to one of said drive-shaft sections, each of said drive-shaft sections being provided with separately operable braking means. 70

4. In an air-ship, the combination with a supporting frame and motor, of a plurality of forwardly located propellers and a plurality of rearwardly located propellers, arranged to operate in parallel vertical planes; each forwardly-located propeller being connected to a rearwardly-located propeller by motor-driven differential gearing. 80

5. In an air-ship, the combination with a supporting frame and motor, of a front-propeller shaft and an alined rear-propeller shaft, said shafts being connected by motor-driven differential gearing. 90

In testimony whereof we affix our signatures.

HARRY N. ATWOOD.
DAVID D. STERNBERGH.
